UNITED STATES PATENT OFFICE.

WILLIAM O. HICKOK AND ALBERT COOPER, OF HARRISBURG, PENNSYLVANIA; SAID COOPER ASSIGNOR TO SAID HICKOK.

IMPROVEMENT IN BOOK-STABBING MACHINES.

Specification forming part of Letters Patent No. 178,147, dated May 30, 1876; application filed May 10, 1876.

To all whom it may concern:

Be it known that we, W. O. HICKOK and ALBERT COOPER, of Harrisburg, in the county of Dauphin, and in the State of Pennsylvania, have invented certain new and useful Improvements in Stabbing-Machines; and do hereby declare that the following is a full, clear, and exact description thereof, reference being had to the accompanying drawings, and to the letters of reference marked thereon, making a part of this specification.

The nature of our invention consists in the construction and arrangement of a stabbing-machine, as used by book-binders, as will be hereinafter more fully set forth.

In order to enable others skilled in the art to which our invention appertains to make and use the same, we will now proceed to describe its construction and operation, referring to the annexed drawing, in which—

Figure 1 is a front view of the stabbing-machine head embodying our invention. Figs. 2 and 3 are cross-sections of the same through the lines *x x* and *y y*, respectively. Fig. 4 is a detached view of parts thereof.

A represents the head of the stabbing-machine, provided with the shank or arm *B*, which is placed in suitable guides, so as to have a vertical reciprocating motion. The head *A* is slotted or grooved longitudinally from its lower edge upward for a suitable distance, and in the groove thus formed are placed the needles *C C*, division-plates *D D*, and the bar *G*. The needles *C C* are of the usual construction, and provided across their upper ends with a groove, *a*, as shown in Fig. 4. Between these needles are placed the division-plates *D D*, of any suitable length, so as to bring the needles any desired distance apart. These plates are also grooved on the front side, near the top, to form with the grooves *a* in the needles one continuous groove. In front of the needles and division-

plates is then placed the bar *G*, which has on its rear side, near the top, a longitudinal rib or tongue, *b*, which lies in the groove formed on the needles and division-plates. This bar or plate *G* is held to the front portion of the head *A* by means of a screw, *d*, at each end, passing through a recess in the head, as shown in Fig. 3. In this recess, around the screw *d*, is a spiral spring, *i*, the action of which is to draw the plate *G* away from the needles and division-plates; but there is not room in the head to entirely remove the tongue or rib *b* from the groove *a*, and hence the needles and division-plates will not fall out, but can be moved easily laterally toward either end of the head. The bar or plate *G* is pressed down, to hold the needles and division-plates firmly in position, by means of set-screws *h h*, as shown. As soon as these set-screws are loosened the springs *i i* at once draw the bar or plate *G* outward, so that the needles and division-plates may be changed without trouble.

Having thus fully described our invention, what we claim as new, and desire to secure by Letters Patent, is—

1. The combination, with the grooved or slotted head *A*, of the needles *C* and division-plates *D*, having grooves *a*, as described, the plate or bar *G*, having tongue or rib *b*, and the set-screws *h*, substantially as and for the purposes herein set forth.

2. The set-screws *d d* and the springs *i i*, in combination with the bar *G* and recessed head *A*, substantially as and for the purposes herein set forth.

In testimony that we claim the foregoing we have hereunto set our hands this 27th day of April, 1876.

W. O. HICKOK.
ALBERT COOPER.
